Primary Examiner — George D Kirschbaum*Assistant Examiner* — Natasha Vujcic(74) *Attorney, Agent, or Firm* — Koppel, Patrick, Heybl & Philpott(57) **CLAIM**

The ornamental design for a linear wrap light fixture, as shown and described herein.

DESCRIPTION

FIG. 1 is a front perspective view of the present invention; FIG. 2 is a right end elevation view, with the left end being a mirror image thereof;

FIG. 3 is a front elevation view thereof;

FIG. 4 is a top elevation view with the opposite side being a mirror image thereof;

FIG. 5 is rear elevation view thereof; and,

FIG. 6 is a perspective view thereof.

The broken lines in the drawings illustrate portions of the linear wrap light fixture which form no part of the claimed design.

The break lines in FIG. 6 indicate that the appearance of any portion of the liner indirect asymmetric light fixture between the break lines forms no part of the claimed design.
